UNITED STATES PATENT OFFICE.

WILLIAM B. MACK, OF EAST BOSTON, MASSACHUSETTS.

INJECTOR.

SPECIFICATION forming part of Letters Patent No. 439,356, dated October 28, 1890.

Application filed August 10, 1889. Serial No. 320,341. (Model.)

To all whom it may concern:

Be it known that I, WILLIAM B. MACK, of East Boston, in the county of Suffolk and State of Massachusetts, have invented certain 5 new and useful Improvements in Injectors, of which the following is a specification.

This invention has for its object to provide certain improvements in injectors, principally with relation to the combining and delivery cones thereof, whereby injury to said parts by expansion and contraction at the point where they are connected with each other is prevented and the operation of applying the combining-cone to the injector is simplified.

15 To these ends the invention consists in the combination, with the other operative parts of the injector, of a delivery-cone and a combining-cone fitted to be engaged with each other without a positive or screw-thread connection, the combining-cone having a reduced unthreaded cylindrical end or boss and the delivery-cone an unthreaded socket formed to receive said end, so that independent expansion or contraction of either of said cones 20 can take place without strain on the other or on the connection between them, the end of the combining-cone being adapted to slide in the socket of the delivery-cone.

The casing or shell of the injector is provided with a seat or shoulder at the larger or receiving end of the combining-cone, and said cone has an outwardly-projecting flange which bears on said seat, the latter supporting the receiving end of the combining-cone.

35 The invention also consists in certain improvements in the construction of that part of the shell or casing that incloses the combining-cone, said shell being contracted around the combining-cone to reduce the size of the 40 water-space surrounding said cone, and provided with an annular enlargement surrounding the overflow-orifices between the combining and delivery cones, said enlargement affording a channel of sufficient size for the 45 passage of the overflow-water to the overflow-outlet.

In the accompanying drawings, forming a part of this specification, Figure 1 represents a longitudinal section of an injector provided 50 with my improvements. Figs. 2 and 3 represent side views respectively of the combining-cone and the delivery-cone. Fig. 4 rep-

resents a longitudinal section of an injector of slightly different pattern, having my improvements so far as the same relate to the 55 combining and delivery cones.

In the drawings, *a* represents the combining-cone, *b* the delivery-cone, and *c* the shell or casing. These and the other operative parts of the injector are arranged, as usual, 60 with relation to each other, and the injector operates in the usual manner. The combining-cone is provided at its smaller end with a cylindrical boss *a'*, extending from a shoulder 2 to the end of said cone, said boss presenting 65 a smooth periphery, which takes the place of the screw-thread usually formed on the combining-cone at this point. The delivery-cone is provided with a socket *b'*, having a smooth internal surface formed to receive and fit 70 closely upon the boss *a'*, said smooth-surfaced socket taking the place of the internal screw-thread usually formed in the delivery-cone. It will be seen, therefore, that when the boss of the combining-cone is inserted in 75 the socket of the delivery-cone the engagement of said cones with each other is not positive, but is such that either can move independently of the other by expansion and contraction. Hence there is no strain on either 80 part or on the connection between the parts by the independent expansion or contraction of either or by the expansion and contraction of the casing, the smooth boss and socket constituting a slip-joint, which makes the 85 cones independent of each other so far as expansion and contraction are concerned. The delivery-cone is threaded at 3 and screwed into the end coupling or fitting 4 of the injector in the usual manner.

90 5 are the usual overflow-openings in the delivery-cone.

The combining-cone is provided at its larger end with an outwardly-projecting flange 6, which rests on a seat or shoulder 7, formed 95 on the interior of the casing *c*, there being no positive connection between said casing and the combining-cone, so that the latter can be easily inserted in and removed from the casing. The portion 8 of the casing that surrounds the overflow-openings 5 of the delivery-cone is made of the usual diameter, but the portion 9 of the casing that surrounds the combining-cone is contracted, so that the 100

space between the casing and the exterior of the combining-cone is much narrower than usual and can therefore contain comparatively little water.

5 An advantage of the contracted casing is that there is less liability of injury to the casing by freezing of water surrounding the combining-cone than there would be if the entire casing were made of the usual internal diameter. The enlarged portion 8 of the casing constitutes an annular channel for the passage of the overflow-orifice to the waste or outlet nozzle.

In Fig. 4 I have shown an injector of slightly different pattern, having the same operative parts, but without the contracted casing.

I claim—

1. The combination, with the casing and other operative parts of an injector, said casing having an internal seat or shoulder 7, of the combining-cone having at its larger end a flange formed to bear on said seat and at its inner end an unthreaded cylindrical boss, and

the delivery-cone positively secured to the casing and having an unthreaded socket 25 formed to receive said boss, as set forth.

2. In an injector, the combination, with the casing having an internal seat or shoulder 7, of the combining-cone having at its larger end a flange formed to bear on said seat and 30 at its inner end an unthreaded cylindrical boss, the delivery-cone having at one end an unthreaded socket formed to receive said boss, its other end being provided with a screw-thread, and the end coupling or fitting 35 having its inner end engaging said threaded end of the delivery-cone and secured fast to said casing, as set forth.

In testimony whereof I have signed my name to this specification, in the presence of 40 two subscribing witnesses, this 22d day of July, A. D. 1889.

WILLIAM B. MACK.
